(57) CLAIM

The ornamental design for a golf club head face insert, as shown and described.

DESCRIPTION

FIG. 1 is a front elevational view of the golf club head face insert claimed herein;

FIG. 2 is a top plan view thereof; and,

FIG. 3 is a cross-sectional view of the golf club head face insert shown in FIG. 1 along lines 3-3.

The broken showing of portions of the putter head is included for the purpose of illustrating unclaimed subject matter and forms no part of the claimed design.
